UNITED STATES PATENT OFFICE.

RICHARD J. JOHNSTON, OF SOUTH BEND, INDIANA, ASSIGNOR TO GEORGE CUTTER COMPANY, A CORPORATION OF INDIANA.

GLOBE HOLDER.

Application filed September 13, 1924. Serial No. 737,474.

My invention relates to lighting fixtures and particularly to a holder for mounting a shade and globe on a support or a suspended member.

5 Lighting fixtures that are provided with a shade and a globe are often attached to the husk by a number of screws or other separately-acting devices that require a number of manual operations in assembling the fixture. A desirable feature, particularly in 10 large fixtures, is to avoid such structures and to provide means comprising a small number of parts that can be easily and quickly operated to assemble and disassemble the globe and shade, so that all of the 15 rather cumbersome parts may be secured together in a single operation.

In large globes there is usually some irregularity in the size and shape of the globe 20 flange and there is also considerable contraction and expansion by reason of heating and cooling of the globe, which causes breakage of the globes where the flange is rigidly clamped. I provide a holder which adjusts 25 itself to such irregularities and which permits a limited amount of expansion and contraction of the globe.

It is, therefore, one object of my invention to provide a holder which shall attach 30 all the parts in one operation, and which shall adjust itself to the irregularities in the globe and the shade.

Another object of my invention is to provide a globe holder which shall positively 35 unite the globe, shade and support, and shall provide means for the expansion and contraction of the globe after it is mounted.

Still another object of my invention is to provide a globe holder which shall comprise 40 a small number of parts and shall be inexpensive to manufacture.

In the drawings constituting a part hereof and in which like numerals designate like parts,

45 Fig. 1 is an elevational view partly in cross section, of a lighting fixture.

Fig. 2 is a top plan view of the keeper ring, and

50 Fig. 3 is a bottom plan view of the support.

Fig. 4 is an enlarged view of a portion of Fig. 1, showing in detail the manner of attaching the globe and shade.

55 The illustrated lighting fixture comprises a bell-shaped support or husk 1 in which a

lamp 2 is mounted and from which a globe 3 and a shade 4 are suspended. The support 1 is provided with an inwardly turned flange 5 and with an upturned circular flange or collar 6 that is provided with pins 60 7 spaced 180° apart. The shade and globe are supported by means of a keeper-ring, which comprises a collar member that is adapted to fit into the upturned flange 6. The collar member 8 is provided with two 65 L-shaped slots 11 that cooperate with the pins 7 for attaching and locking the keeper-ring. The collar 8 is further provided at its lower end, with an outwardly turned flange 10, upon which are riveted flat or leaf springs 70 12 that bear against the under side of the globe flange 12a and hold the globe and shade in place in a resilient manner.

The flange 5 on the collar 6 is provided with a pair of double key hole slots 13, 75 which co-operate with a pair of pins 14 having enlarged ends and attached to shade 4, for loosely supporting the shade from the husk 1 when the keeper-ring and globe are removed.

80 The fixture is assembled by first loosely attaching the shade 4 to the flange 5 by inserting pins 14 in the enlarged portions 15 of double key hole slots 13, and then turning the shade so that the pins are in the 85 small ends 13 of the slots. The globe 3 is then raised by means of the keeper-ring, and the pins 7 are entered in slots 11. By turning the keeper ring, the pins are locked in notches 16 or 17, as the case may be, according 90 to whether the shade or globe alone or both shade and globe are mounted. The springs 12 bear against the glass globe to thereby unite the shade and globe, but in such manner that irregularities in the globe 95 flange are compensated for by the springs 12, and a slight movement of the globe, by reason of its expansion or contraction, is permitted. If desired, a washer 18 may be inserted between the globe and shade. 100

My invention thus provides means for positively holding the shade and globe. The holder allows expansion and contraction of the glass parts as well as a considerable variation in the size and shape of the glass 105 flange of the globe, without causing it to break.

Although I have described a specific embodiment of my invention, I do not wish to be limited thereto, since my structure may 110

be modified in various ways. For example, a different type of spring, such as a coil spring, may be used in place of the spring that I have shown. Other modifications will suggest themselves to those skilled in the art without departing from the spirit of my invention, the scope of which is defined in the annexed claims.

I claim as my invention:

19. 1. A lighting fixture comprising a globe, a shade, a support, a circular collar in said support, means in said shade and collar for loosely suspending said shade, a flanged ring supported in said collar, and means on said flanged ring for resiliently supporting said globe and shade.
20. 2. A lighting fixture comprising a globe, a shade, a support, a flanged circular collar extending upwardly in said support, means in said shade and collar for loosely suspending said shade, a flanged ring supported in said collar, and means on said flanged ring for resiliently supporting said globe and shade.
21. 3. A lighting fixture comprising a globe, a shade, a support, a circular collar in said support, bayonet slots in a portion of said collar and pins in said shade for loosely suspending said shade, a flanged ring supported in said collar, and means on said flanged ring for resiliently supporting said globe and shade.
22. 4. A lighting fixture comprising a globe, a shade, a support, a slotted circular collar in said support, means in said shade and collar for loosely suspending said shade, a

ring fitted in said collar, slots in said ring cooperating with pins in said collar for attaching and locking said ring, an outwardly extending flange on said ring, and springs on said flange for pressing against said globe and resiliently supporting said globe and shade.

5. A lighting fixture comprising a globe, a shade, a support, a circular member in said support embodying an outwardly extending flange and a receptacle, means cooperating with said outwardly extending flange for loosely attaching said shade, and means comprising a collar and an outwardly extending flange adapted to be fastened and locked in said receptacle for resiliently uniting said globe, shade and support.

6. A lighting fixture comprising a globe, a shade, a support, a circular member in said support having an outwardly extending slotted flange and a receptacle therein, pins in said shade co-operating with the slots in said outwardly extending flange for loosely suspending said shade, a slotted collar member interiorly disposed in said receptacle, pins in said receptacle, co-operating with the slots in said collar for uniting and locking said receptacle and collar, an outwardly turned flange on said collar member, and springs on said outwardly turned flange for resiliently supporting said globe and shade.

In testimony whereof, I have hereunto subscribed my name this 2nd day of September, 1924.

RICHARD J. JOHNSTON.
